UNITED STATES PATENT OFFICE.

WILLIAM A. GEIGER, OF CHICAGO, ILLINOIS, ASSIGNOR TO W. H. MINER, INC., OF CHICAGO, ILLINOIS, A CORPORATION OF DELAWARE.

DOOR-OPERATING MECHANISM.

Application filed June 10, 1926. Serial No. 115,070.

This invention relates to door-operating mechanisms.

One object of the invention is to provide a simple and efficient door operating mechanism for forcing the door when partly closed to tightly closed position, for holding the door closed, and for forcing the same open to facilitate the complete opening thereof.

Another object of the invention is to provide a door operating mechanism especially adapted for pivoted doors of refrigerator cars, including oppositely disposed, vertically reciprocable, laterally movable, actuating members operated from a common lever means, and adapted to cooperate with horizontally arranged keepers for moving said door in opening and closing directions, and for retracting the end portions of said members to a position within the confines of the door when the mechanism is operated to open said door so as to clear the usual loading platforms.

Other and further objects of the invention will more clearly appear from the description and claims hereinafter following.

In the drawings forming a part of the specification, Fig. 1 is a side elevational view of a portion of a refrigerator car showing my improvements in connection therewith. Fig. 2 is a vertical, sectional view on an enlarged scale, partly broken away, corresponding substantially to the line 2—2 of Fig. 1, showing the position of the parts of the mechanism when the door is tightly closed. Fig. 3 is a part sectional, part elevational view, of the lower end of one of the operating members and the related guide member and keeper, said view being taken substantially upon the line 3—3 of Fig. 1. Fig. 4 is a part sectional, part elevational view of the bottom keeper and lower end of the operating member substantially on the line 4—4 of Fig. 1 and showing the door in dotted lines in partly open position. Fig. 5 is a fragmentary side elevational view, somewhat similar to Fig. 1, showing a slightly different embodiment of the invention. And Fig. 6 is a top plan view of the type of keeper used in connection with the construction shown in Fig. 5.

In said drawings, the side of the car is shown as provided with a door frame 10, and two pivoted doors 11 and 12. The doors have the usual beveled meeting edges

and the customary insulation or packing is employed between the meeting edges of the doors and the remaining edges of the doors, and door frame. The doors 11 and 12 are mounted for swinging movement about vertical axes, being supported by suitable hinges 13—13.

The door operating mechanism comprises broadly operating members A—A; operating lever B; guide brackets C—C; and keepers D—D.

The door operating members A—A are two in number, each of the same being in the form of a flat bar substantially rectangular in cross section, one of said members being arranged adjacent the upper end of the door 12, while the other member is arranged adjacent the lower end of the door 12. The upper end of the upper member A fits into a forked end casting 14, said end casting being provided with an enlargement 15 adapted to abut against the upper guide bracket C and having a stem 16 projecting through the upper guide bracket C and is adapted to cooperate with the upper keeper D. The lower end of the other operating member is also provided with a similar casting 140 having a stem portion 160 projecting through the lower guide bracket C, and adapted to coact with the lower keeper D.

Means are provided for mounting the members A—A for combined longitudinal reciprocal and lateral movement, said means including a link or transmitting member 17 pivotally mounted upon the door 12 intermediate its ends as indicated at 190, one end portion of said link being pivotally connected with the upper operating member A somewhat inwardly from the end casting 14 as indicated at 18. The inner end of the lower member A is pivotally connected to the opposite end of the link 17 as indicated at 19.

Adjacent the lower end of the door 12, there is mounted the lever or transmitting member B adapted to swing about the pivot 20, the point of pivotal mounting of the lever B being arranged somewhat inwardly from the end of said lever, providing an end portion, indicated at 21, which is pivotally connected to the lower member A somewhat inwardly from the end casting 140 thereon, as indicated at 22. The lower end of the upper member A is also pivotally connected to the lever B at the point indicated at 23,

the distance between the pivots 23 and 20 and 22, corresponding to the distance between the pivots 18, 190 and 19. The lever B is provided with a handle 24 by which the 5 same may be actuated to effect combined reciprocal and lateral movement of the operating members A—A as will be understood.

The guide brackets C—C are two in number, one of the same being adapted to co-operate with the upper end casting of the upper member A, said guide bracket including a plate and a strap mounted thereon defining an elongated guideway for the 15 upper end of the upper member A to permit both longitudinal and lateral movement of said end. The lower bracket C is identical in construction with the upper bracket C and is associated with the bottom end of 20 the lower member A, and permits combined longitudinal and lateral movement of the lower end of said bar.

The keepers D—D are two in number, one of the same being secured to the door frame 25 adjacent the upper end of the upper member A, while the other keeper is arranged adjacent the lower end of the lower member A. The lower keeper D is secured to the door frame by suitable bolts indicated at 25—25, and said keeper is provided with 30 upstanding portions 26—26 defining a cam slot 27, which is arranged in a horizontal direction and opens outwardly toward the free edge of the door 12, said cam slot 27 being adapted for the reception of the stem 160 of the end casting on the lower operating member A. The lower keeper D is provided with an extension upon which is mounted a pivoted latch 28, said latch being 35 adapted to bear against a wear plate 29 secured to the lower right hand corner of the door 11. The upper keeper D is of identically similar construction to the lower keeper except that the cam slot 30 thereof 40 opens inwardly away from the free edge of the door 12, the cam slot 30 being adapted to cooperate with the stem 16 of the upper bar A when the mechanism is operated.

50 A bracket 31 is secured to the door 11 and is provided with a laterally extending flange 32 provided with an aperture adapted to coact with a similar aperture arranged in a flange formed upon the handle 24 of the lever B, said apertures being adapted for the reception of a locking or sealing member.

In operation, assuming the doors to be 55 closed as illustrated in Figs. 1 and 2 of the drawings, and it is desired to open the same, upon movement of the handle 24 of the lever B in a counter-clockwise direction, as shown in dotted lines in Fig. 1, reciprocal movement in opposite directions will 60 be imparted to the operating members A,

and simultaneously due to the pivotal connections between said operating members, the same will approach each other, bringing about lateral movement of the end castings of the operating members as well as 70 longitudinal movement thereof, thereby causing traverse of the cam surfaces of said keepers in a horizontal as well as vertical direction, and effecting opening movement of the door sufficient to clear the insulation between the edges thereof, after which the door 12 may be moved to fully opened position. During this action, it should be noted that the end casting on the lower operating bar will have been elevated by 75 so the movement of the actuating lever so that the same is disposed in a position within the confines of the door, and said operating members will be held in such position, so long as the door is open, due to the influence 80 of gravity acting upon the operating lever which hangs in a depending position, and hence maintains the operating end of the lever at a position within the bottom edge of the door, thereby removing any obstructions 85 from said edge to permit ready clearance of loading platforms when the door is opened. When the door 12 has been fully opened the latch 28 may be swung out of engagement with the wear plate 29 after 90 which the door 11 may be readily opened to its full extent.

When it is desired to close the doors, the door 11 is swung to nearly closed position, after which the door 12 is swung in a closing direction until the opposite end portions of the operating members A—A are in alinement with the upper and lower keepers and in position to enter the cam slots thereof. When the actuating portions of the operating members A—A are in position to 100 enter the keepers, the actuating lever B is swung in a clockwise direction by its handle 24, which effects reciprocation of said operating members vertically outwardly in 105 opposite directions, and at the same time causes said operating members to move away from each other and impart a combined vertical and horizontal movement to the end castings of the operating members, causing the same to traverse the cam surfaces of the horizontally arranged keepers so as to force the doors 11 and 12 to fully closed position, after which the pivoted latch 28 may be 110 turned against the wear plate 29 to lock the door 11 in closed position. The handle of the lever B then may be reengaged with the locking means 32.

Referring now to Figs. 5 and 6, a somewhat different embodiment of the invention is disclosed. In this arrangement, doors 35 and 36 are provided mounted in a door frame 37 in identically the same manner referred to in connection with Figs. 1 to 4 115

inclusive. Mounted upon the door 36 is an operating mechanism consisting of operating bars 38-38, corresponding to the members A-A shown in Fig. 1, and although only the lower portion of the operating mechanism is disclosed, it will be appreciated that said mechanism is identically similar to that shown in Fig. 1, except as herein-after otherwise pointed out. The outer end 10 of each of the members 38-38 is provided with an end casting indicated at 39 which is the same in all respects to the castings 14 and 140 heretofore referred to, except that the stem of each casting as indicated 15 at 40 in Fig. 5 is of considerably greater length than the stems 16 and 160, the bars 38-38, of course, being shorter than the bars A-A to permit the use of the longer stems indicated at 40 to provide operating 20 members which in overall length are exactly similar to the operating members A-A.

Guide brackets similar to the guide brackets C-C heretofore described are provided 25 as indicated at 41, and in each of said guide brackets an elongated stem 40 is disposed for combined reciprocal and lateral movement. The lower operating member 38 is provided with a pivoted latch 42 which in 30 one position of the lower bar 38, engages with a projection 43 formed upon the outer face of the lower guide bracket 41.

Mounted upon the door frame 37 adjacent the upper and lower ends of the operating 35 members 38-38 are keepers, the lower of which is indicated at 44, said keepers being adapted to co-act with the stems upon the opposite ends of the operating members 38-38. The lower keeper 44 is provided 40 with vertically disposed walls defining a cam slot 45 which is open at its top and bottom, and which has an entrance facing the forward edge of the door 36, the cam slot 45 being adapted for the reception of 45 the elongated stem 40 on the lower operating member 38. The keeper 44 is extended to the left and provided with a latch 46 adapted to be turned against the wear plate 47 secured to the lower right hand corner 50 of the door 35. A keeper similar to the keeper 44 is associated with the upper portion of the door frame and is adapted to 55 cooperate with the stem of the upper operating member 38, said upper keeper having a cam slot similar to the cam slot 45 except that said cam slot has an entrance disposed away from the forward edge of the door in the same manner as the upper keeper D disclosed in Fig. 1. A bracket 60 48 is secured to the door 35 and adapted to cooperate with the handle 49 by which the operating members 38-38 are actuated, the bracket 48 being provided with an apertured rib 50 adapted for the reception of 65 a sealing member which may be extended

about the handle 49. Said handle is provided with an offset indicated at 51 which will permit the handle 49, when the sealing member is absent, to swing past the rib 50 to the dotted line position shown in Fig. 5. 70

In operation, assuming the doors to be closed as shown in Fig. 5, and that it is desired to open said doors, the handle 49 may be moved downwardly in the manner heretofore described in connection with 75 Figs. 1 to 4 inclusive, causing traverse by the stems on the end castings of the keepers to force the door in an opening direction. If on the other hand convenience requires that the handle 49 be swung upwardly or 80 in a clockwise direction, toward the position indicated in dotted lines, this movement will effect combined reciprocation of the members 38-38 and simultaneous approach 85 thereof substantially in parallel relation, this movement also causing traverse of the cam surfaces of the keepers to force the door open. During the downward movement of the lower operating bar 38, the pivoted latch 42 rides over the projection 90 43 and effectively prevents the return of the mechanism to the position indicated in Fig. 1 in dotted lines, under the influence of the weight of the handle 49. If it is desired, the latch 43 may be disengaged to 95 permit the mechanism to assume the position indicated in dotted lines in Fig. 1 so that the projecting ends of the stems will be retracted to points within the confines of the door. However, it will be noted that 100 the latch holding the mechanism in the position shown in dotted lines in Fig. 5, maintains the mechanism in such position that no further movements of the operating handle 49 are necessary to arrange the stems 105 on the operating members in position to re-enter the keepers, after which the handle 49 may be swung downwardly to cause traverse of the keepers about the stems and force the door to tightly closed position. 110

While I have herein shown and described what I now consider the preferred manner of carrying out my invention, the same is merely illustrative, and I contemplate all changes and modifications that come within 115 the scope of the claims appended hereto.

I claim:

1. In a door operating mechanism, the combination with a door and a door frame therefor; of an operating member having an actuating portion adapted to project beyond one edge of said door and a second operating member adapted to project beyond the opposite edge of said door; transmitting members pivotally mounted intermediate the ends thereof and arranged in spaced relation, one end portion of one of said transmitting members being connected with one end portion of one of said operating members, and the opposite end portion thereof 130

being pivotally connected with the second operating member at a point between its ends, and the other transmitting member having one end portion connected with said 5 first mentioned operating member intermediate its ends, and having its opposite end portion pivotally connected with the end portion of said second operating member; means for swinging said transmitting members about their pivots; and keeper means adapted to co-act with said operating members to effect movement of said door in opening and closing directions.

2. In a door operating mechanism, the 15 combination with a door and a door frame therefor; of an operating member having an actuating portion adapted to project beyond one edge of said door, and a second operating member adapted to project beyond the 20 opposite edge of said door; transmitting members pivotally mounted intermediate the ends thereof and arranged in spaced relation, one end portion of one of said transmitting members being connected with one 25 end portion of one of said operating members, and the opposite end portion thereof being pivotally connected with the second operating member at a point between its ends, and the other transmitting member 30 having one end portion connected with said first mentioned operating member intermediate its ends, and having its opposite end portion pivotally connected with the end portion of said second operating member, 35 said other transmitting member having an extension providing a lever for effecting movement of said operating members.

3. In a door operating mechanism, the 40 combination with a door and a door frame therefor; of an operating member having an actuating portion adapted to project beyond end edge of said door, and a second operating member adapted to project beyond the 45 opposite edge of said door; transmitting members pivotally mounted intermediate the ends thereof and arranged in spaced relation, one end portion of one of said trans-

mitting members being connected with one end portion of one of said operating members, and the opposite end portion thereof being pivotally connected with the second operating member at a point between its ends, and the other transmitting member having one end portion connected with said first mentioned operating member intermediate its ends, and having its opposite end portion pivotally connected with the end portion of said second operating member, 50 said other transmitting member having an extension providing a lever for effecting 55 movement of said operating members; and keeper means cooperating with the projecting portions of said operating members to effect movement of said door in opening and closing directions. 60

4. In a door operating mechanism, the combination with a door frame and a pivoted door; of a pair of elongated operating bars mounted on said door, disposed side by side, each of said members having an actuating portion adapted to project beyond one edge of said door; means for effecting reciprocation of said members in a longitudinal direction and simultaneously effecting approach and recession of said members laterally with respect to each other, said means including a guiding member pivoted to both bars and said door, and an actuating member pivoted on said door and also pivoted to both bars; and keeper means mounted on said 70 door frame and cooperating with the projected end portions of said operating bars to effect movement of said door in opening and closing directions, said operating means being effective to retract the actuating portion at the lower edge of said door to a 75 position within the confines thereof when the door is moved in an opening direction, by said operating bars. 80

In witness that I claim the foregoing I 85 have hereunto subscribed my name this 2nd day of June, 1926.

WILLIAM A. GEIGER.
